JAMES H. WAGENHORST, OF JACKSON, MICHIGAN.

METHOD AND APPARATUS FOR MAKING WHEELS.

Application filed February 24, 1920. Serial No. 360,804.

This invention relates generally to wheels, and more particularly to the method of, and apparatus for making a wheel consisting of wooden spokes and a sheet metal felly, the object being to provide a simple method of making such a wheel, and likewise a simple and efficient apparatus for fabricating the wheel according to such method. Briefly described the method consists in enlarging the sheet metal felly, positioning the spokes within said enlarged felly, with the tenons of said spokes engaging the sockets in said felly and their mitered ends in close proximity to one another, said mitered ends being elevated above the plane of the felly; and while said felly is still in its enlarged condition forcing said mitered ends into the plane of said felly thus bringing all of the spokes into the true plane, and finally permitting the felly to contract or assume its normal size, thereby placing all the spokes under radial compression and bringing the mitered ends into proper binding engagement with one another.

The invention consists also in providing a suitable fixed support for the sheet metal felly, a yieldable support for the inner or mitered ends of the spokes and a guide for positioning the outer ends of said spokes, and means for forcing down the yieldable support with the mitered ends of the spokes thereon until all of the spokes have been brought into the plane of the felly. The invention consists also in certain details of construction hereinafter fully described and set forth in the claims.

In the drawings forming a part of this specification Fig. 1 is a perspective view of a machine embodying one form of apparatus for making wheels of the kind described and for carrying out my improved method; Fig. 2 is a general view showing the sheet metal felly arranged upon the support and the spokes positioned within the felly and supported in their elevated position upon the wheel support; Fig. 3 is a sectional elevation showing the positions all the various parts assume when the plunger is forced down bringing the spokes into their final positions in the plane of the felly; Fig. 4 is a top plan view of the felly support together with spoke support and guide and Fig. 5 is a detailed view showing a slightly modified form of combined felly support and guide. In the practical embodiment of my invention I employ a suitable standard 10, to which is connected in any suitable manner, a horizontal table or support 11, which in practice is preferably circular in shape and of such size as to conveniently receive thereon a sheet metal felly 12 which is made with a valve stem hole and a plurality of spoke sockets 13. The table or support 11 has a guide ring 14 connected thereto, said ring being of such size that the sheet metal felly 12 when expanded will fit accurately thereover, and it will be understood that for various sizes of fellyes there will be corresponding varying sizes of guide rings. Each guide ring has a plurality of 15 radial notches as many as there are spokes for the wheel. The ring may also be provided with an outwardly projecting pin 16 to enter the valve stem hole of the felly and determines the accurate positioning of 20 the felly upon the support so as to bring the spoke sockets in direct alignment with the notches 15; and the table or support is also provided with parallel upwardly extending guide pins 17 between which the first spoke 25 25 is positioned, the outer ends or tenons 19 being placed in engagement with the spoke socket 13, while the mitered ends 20 rest upon the head 21 of a yielding support 22 arranged centrally of the table 11 and normally supported in a raised position by means of a spring 23 held within a depending bracket 24 connected to the table 11; and it will be noted that the outer edge of the head 21 is beveled as shown at 25 there 30 being as many bevels as there are spokes for the wheel, and the mitered end of each spoke rests upon this beveled edge and is thereby maintained in its proper position within the felly preparatory to being 35 brought into the true wheel plane by means of a plunger 25 actuated by a fluid operated piston arranged in the cylinder 27, the plunger preferably having a reduced lower end 28 which passes between the inner ends 40 of the spoke miters and serves to maintain them properly positioned during the shifting of said spokes from the inclined position illustrated in Fig. 2 to the horizontal position illustrated in Fig. 3. If desired, a 45 suitable depending guide 29 may be attached to the bottom of the cylinder 27 for the purpose of guiding the plunger and piston and also serving as a stop to limit the upward movement thereof. The cylinder 27 50 can receive either hydraulic or air pressure. I have shown a pipe 30 leading into the op-

posite ends thereof controlled by a valve 31 operated by a handle 32, but it will be understood any suitable arrangement may be used for causing the piston and plunger to raise and lower when desired in order to effectively accomplish the operation of the machine and carry out this step in the process. After the spokes have been forced down into the wheel plane as illustrated in Fig. 3 pressure is removed from the plunger and the wheel comprising the felly and spokes in their proper plane is then removed from the support. Before the felly is placed upon the table 11 it is heated sufficiently to cause a considerable expansion and when so expanded is fitted about the guide ring 14 upon the table and the spokes arranged therein in umbrella fashion as shown in Fig. 2 and then brought down into the true wheel plane as shown in Fig. 3 and after the removal of the wheel from the machine, the felly is permitted to cool and contract and in doing so resumes its normal size and places all of the spokes under the proper radial compression and binding their mitered ends into proper contact and providing a wheel of great strength and durability. In Fig. 5, I have shown a slight modification of guide ring 14^a arranged upon the table 11, said guide ring being shouldered as indicated at 14^b to receive the sheet metal felly therein instead of arranging the sheet metal felly upon the exterior thereof as indicated in Fig. 3. So far as the operation of the machine and carrying out the method, however, are concerned, the functions and operations of this guide ring are substantially the same as that previously described so far as the positioning of the felly is concerned, but it does not serve as a guide for positioning the spokes. When the spokes are forced down there is a tendency to distort the rim slightly outwardly at the spoke ends and slightly inwardly between the spoke ends, and the rings 14 and 14^a will hold these distortions within certain limits, and when the pressure is relieved and the rim removed the rim in recovering from these slight distortions will aid in tightening the wheel. By practicing the method herein set forth, and by the operation of the machine herein shown and described I am able to quickly and efficiently manufacture a wheel consisting of a sheet metal felly and wooden spokes, said spokes preferably having tenoned outer ends and mitered inner ends of the standard type. It is obvious that certain changes and modifications can be made to the apparatus herein shown within the scope of the appended claims.

Having thus described my invention, what I claim is:

1. The herein described method of producing a wheel body comprising a channeled

sheet metal rim and a plurality of wooden spokes, said method consisting in positioning an enlarged felly upon an annular support and maintaining the same against material distortion, arranging the wooden spokes within the sheet metal rim, their outer ends being in engagement with said rim at definite points, their mitered ends being elevated above the plane of said rim and then bringing the inner ends of said spokes into the plane of the wheel and finally permitting the sheet metal rim to resume its normal size and shape and place the spokes under radial compression.

2. The herein described method of producing a wheel body comprising a channeled sheet metal felly and a plurality of wooden spokes which consists in positioning a heated sheet metal rim upon a suitable annular support and holding the same against material distortion, arranging the wooden spokes with their outer ends in engagement with said rim and their mitered ends elevated above the plane of said rim and then bringing said spokes into the plane of the rim, while said rim is still held against material distortion and finally permitting said rim to cool and assume its normal size and shape and place the spokes under radial compression.

3. In a machine for making wheels comprising wooden spokes and a sheet metal rim, the combination with an annular rim support, of centrally disposed means for supporting the spokes at their inner ends, the annular rim support being provided with means for positioning and maintaining both the rim and spokes in their correct relative positions, and means for bringing the spokes into the plane of the rim.

4. In a machine for making wheels comprising wooden spokes and a sheet metal rim, the combination with a fixed support including an elevated ring provided with radial notches, of a centrally arranged yieldable support adapted to maintain the inner ends of the spokes in an elevated position while the outer ends contact with the elevated notched ring, and with which the sheet metal rim also contacts, and means for forcing the central spoke support downwardly and bringing the spokes into the plane of the rim held about the notched annular ring.

5. In a machine for manufacturing wheels, comprising wooden spokes and a sheet metal rim, the combination with a rim support comprising a base portion and an elevated ring portion, of means carried by said ring portion for engaging the rim and maintaining the same in a definite position upon said support, a yieldable support for maintaining the mitered ends of the spokes out of the plane of the rim and means for engaging the inner ends of said spokes and bringing them into the plane of the rim.

6. In a machine for making wheels comprising wooden spokes and a sheet metal rim, the combination with a table, of a ring arranged thereon having a plurality of guiding notches, a yieldable support arranged centrally of said table and adapted to support the mitered ends of the spokes, guide pins extending upwardly from the table for positioning the initial spoke, and a plunger adapted to engage the mitered ends of the spokes and bring them into the plane of the sheet metal rim.

7. In a machine for making wheel bodies comprising wooden spokes and a sheet metal rim, the combination with a table, of a ring arranged thereon having a plurality of guiding notches, an outwardly extending pin for the valve stem hole of the rim and determining the position of the rim upon the ring, a pair of guide pins projecting upwardly from the table for positioning the initial spoke, a centrally disposed yieldable support for supporting the mitered ends of the spokes above the plane of the rim, and a plunger adapted to engage said mitered ends of the spokes and bring the same into the plane of the rim.

8. In a machine for making wheels, the combination of a table for supporting a felly, a member thereon serving to preserve the concentricity of said felly, and a depressible support for the inner ends of the spokes, said member having means serving to direct the outer ends of the spokes toward their proper positions in the felly, and means for moving the inner ends of the spokes toward said table.

9. In a machine for making wheels, the combination of a support having means for holding a felly in fixed position thereon, means disposed centrally of and normally elevated above said positioning means for supporting the inner ends of spokes, said support being provided with circumferentially spaced notches for directing the outer ends of the spokes toward their proper position relative to a felly as the inner ends of the spokes are placed upon said centrally disposed means, and means for forcing the inner ends of the spokes toward said support.

In testimony whereof, I hereunto affix my signature.

JAMES H. WAGENHORST.
